UNITED STATES PATENT OFFICE.

JOSEPH M. MELBURG, OF POLO, ILLINOIS.

OUTDOOR COUCH.

1,279,395.

Specification of Letters Patent. Patented Sept. 17, 1918.

Application filed June 12, 1917. Serial No. 174,345.

To all whom it may concern:

Be it known that I, JOSEPH M. MELBURG, a citizen of the United States, residing at Polo, in the county of Ogle and State of Illinois, have invented new and useful Improvements in Outdoor Couches, of which the following is a specification.

This invention relates to a bed couch adapted especially for out-door use and it 10 has for its object to produce a device of this class of simple construction which will be equipped with a screen cover and with a weather-proof cover either of which may be used when required and both of which, 15 when not in use, may be moved to an out-of-the-way position.

A further object of the invention is to produce an out-door couch of the type described having a screen cover and a weather-proof 20 cover, each of semi-circular cross section and suitable guiding means for said covers enabling the same to be moved beneath the body of the bed or couch when not in use.

With these and other ends in view which 25 will readily appear as the nature of the invention is better understood, the same consists in the improved construction and novel arrangement and combination of parts which will be hereinafter fully described 30 and particularly pointed out in the claims.

In the accompanying drawing has been illustrated a simple and preferred form of the invention, it being, however, understood that no limitation is necessarily made to the 35 precise structural details therein exhibited, but that changes, alterations and modifications within the scope of the claims may be resorted to when desired.

In the drawing,— 40 Figure 1 is a view in side elevation of the improved couch showing the screen cover in position for use.

Fig. 2 is a side elevation showing the weather-proof cover in position for use.

Fig. 3 is a side view showing both covers in an out-of-the-way position beneath the body of the couch.

Fig. 4 is a longitudinal sectional view of the device as seen in Fig. 1.

Fig. 5 is a transverse sectional view of the device as seen in Fig. 2.

Fig. 6 is a top plan view of the device as seen in Fig. 3.

Corresponding parts in the several figures 55 are denoted by like characters of reference.

The improved couch is formed of two substantially circular end members 15 each of which has been shown as provided with short legs or supports 16. In Figs. 2 and 5 the end members have also been shown provided with eye bolts 17 with which cables 18 are connected for the purpose of swingingly suspending the couch when desired. The end members 15 are connected together and spaced apart by means of strong braces 60 19 and the said braces together with cleats 20 on the end members 15 are utilized to support a bed bottom 21 of woven wire or other suitable construction.

Firmly secured on the inner face of each 70 end member 15 are two circular flanges 22, 23 said flanges being concentrically disposed and suitably spaced apart to enable the screen cover to be guided therebetween, the weather-proof cover being guided externally 75 on the outer flange 23. The screen cover is composed of two hoops 24 guided between the flanges 22, 23 at each end of the couch, said hoops being connected together and spaced apart by longitudinal frame bars 25, 80 screen material 26 being attached to the hoops and the bars so as to form a screen cover of substantially semicircular cross section or slightly in excess thereof so as to afford ample protection for the occupant 85 of the couch, it being understood that the spring 21 is disposed somewhat beneath the horizontal diameters of the end members in order to afford ample room for the occupant. In like manner the weather-proof 90 cover is composed of hoops 27 guided externally on the outer flanges 23, said hoops being connected together and spaced apart by longitudinal bars 28, the frame structure thus formed being covered with weather- 95 proof material such as canvas which may be suitably treated to render it water-proof.

It will be readily seen that by simply rotating the hoop members at the ends of the respective covers above the respective 100 guide flanges, either the screen cover or the weather-proof cover may be placed in position to protect the occupant of the couch, or both covers may be moved to an out-of-the-way position beneath the body of the 105 couch. The construction of the improved device is simple and inexpensive and it is of such a nature as to enable it to be used out of doors under practically all weather conditions.

It may be stated that when the suspending means are used, the legs or supporting members 16 may be dispensed with.

What is claimed is:—

- 5 1. A couch comprising substantially circular end members, spacing and connecting means for said end members, a bed bottom supported below the horizontal diameters of the end members, concentric circular 10 guide flanges secured on the inner face of each end member and substantially semi-circular cover members guided on said flanges, one of said cover members which is guided on the outermost flange being of a greater 15 radius than the other cover member exteriorly of which it is guided.
2. A couch comprising substantially circular end members, spacing and connecting means for said end members, a bed bottom 20 supported below the horizontal diameters of the end members, concentric circular

guide flanges secured on the inner face of each end member and substantially semi-circular cover members having circular hoops guided on said flanges, one of said cover 25 members being of screen material and the other of weather-proof material.

3. A couch comprising substantially circular end members, spacing and connecting means for said end members, a bed bottom 30 supported below the horizontal diameters of the end members, concentric circular guide flanges secured on the inner face of each end member and substantially semi-circular cover members guided on said flanges, each 35 of said covers being composed of circular hoops guided on the respective flanges, longitudinal bars connecting and spacing said hoops, and cover material secured on the frame thus formed.

In testimony whereof I affix my signature.

JOSEPH M. MELBURG.
